LATCH OPERATING MECHANISM FOR DUMP CARS AND THE LIKE

Einar O. Lunde, Wyckoff, N. J., assignor to Magor Car Corporation, New York, N. Y., a corporation of Delaware

Application January 9, 1947, Serial No. 721,121

7 Claims. (Cl. 105—308)

1

This invention relates to latch operating mechanism for dump cars and the like.

The invention is more particularly concerned with latch operating mechanism for dump cars wherein one or more doors at each side of the car is hinged at its top for outward swinging movement upon transverse inclination of the car and wherein the latch mechanism includes latches normally latching the lower free ends of the doors and which latches are retractable by novel means forming the subject matter of the present application.

In my co-pending application Serial No. 604,877 filed July 13th, 1945, which has matured into Patent No. 2,430,517, November 11, 1947, I disclose latch operating mechanism for the doors of dump cars which includes yieldable means for normally actuating the latches to door latching position and power operable means for releasing the latches against the action of the yieldable means. The structure in accordance with this application is an improvement over that disclosed in my copending application.

The power operable means in the structure of my co-pending application in common with that of the present application is located beneath the dump car and which under most circumstances is satisfactory in the releasing of the latches. It may, however, be of distinct advantage to effect release of the latches from a position above the bottom of the car and without the requirement for power means.

It is accordingly a primary object of this invention to provide latch operating mechanism for top hinged swinging doors on dump cars which includes power operable means for releasing normally closed latches together with manually operable means for effecting release of the latches independently of the power operable means.

A further object of the invention is the provision of a safety lock for restraining release of the latches by either the power or manually operable means.

A still further object of the invention is the provision of latch operating mechanism for top hinged doors of dump cars which is simple in construction, reliable in operation, and which is capable of being constructed at relatively low cost.

The above, together with other objects and advantages of the invention will become apparent in the course of the following detailed description, taken in connection with the accompanying drawings, wherein:

2

Fig. 1 is a fragmental top plan view of the improved latch operating mechanism in position on the bottom of a railway dump car, the base frame of the car being shown in dot-and-dash lines.

Fig. 2 is an enlarged transverse sectional view in the planes of irregular line 2—2, Fig. 1, portions being broken away and the latches being in latching position.

Fig. 3 is a view corresponding to Fig. 2 but with the latches in unlatching position.

Fig. 4 is an enlarged transverse sectional view in the plane of line 4—4, Fig. 1, showing the latch operating mechanism in locked position and particularly illustrating the safety lock mechanism.

Fig. 5 is a view corresponding to Fig. 4 but with the latch operating mechanism in unlocked position, and the safety lock released.

Fig. 6 is a front elevational view of the safety lock in locking position.

Fig. 7 is a view corresponding to Fig. 6 but with the safety lock in unlocking position.

Fig. 8 is a top plan view of the safety lock as shown in Fig. 7.

Referring now in detail to the drawings wherein the invention is illustrated in accordance with a preferred embodiment thereof, F designates the base frame of a railway dump car which is provided with doors D on each side thereof. The frame and doors are shown in dot-and-dash lines for greater clarity of the latch operating mechanism.

At this point, however, it is to be understood that the doors D are hinged at their tops or upper ends as disclosed in my co-pending application and are so hinged as to close by gravity upon a horizontal position of the car.

The plan view of Fig. 1 is substantially that of one-half of a car and with the manually operable means and safety lock mechanism disposed intermediate the ends of the car, or at the extreme right in Fig. 1, and the number of doors D at each side of the car may vary as well as the number of latches cooperating with the free lower end of each door.

An operating shaft 10 is disposed at each side of the longitudinal center line of the car and each shaft is rotatably journaled in bearings 11, 12 and 13 which are rigidly supported from the central portion F' of the frame as indicated, and the shafts preferably extend substantially the full length of the car.

Each shaft 10 is operatively connected with a plurality of latches 14 which as indicated in Figs. 2 and 3 are each in the form of a bell crank pivoted to a bracket 15 at the juncture of its two

arms as indicated at 16. One arm of the bell crank terminates in a keeper lug 17 for engaging a member 18 secured to the lower end of the door. The brackets 15 are rigidly secured to the lateral sides F' of the car frame with the lugs 17 extending laterally thereof and as indicated in Figs. 2 and 3.

The free end of the other arm of the bell crank of each latch is pivotally connected at 18 to a yoke member 19 having a threaded and adjustable connection with one end of a rod 20 whose opposite end is pivotally connected at 21 between the outer ends of arms 22 which are rigidly secured to the shaft 10.

Thus upon consideration of Figs. 2 and 3, it will be seen that oscillation of shaft 10 will rock the latch about its pivot 16 to either the latched position of Fig. 2 or the unlatched position of Fig. 3.

A power operated means is provided for each shaft 10, and each is identified by the character 25. The means 25 for the two shafts 10 are shown as transversely aligned as indicated in Fig. 1, however they may be preferably disposed in diagonally disposed relation whereby either may be operated from one point on the dumper regardless of which way the car is turned.

Each shaft operating means 25, as is more clearly indicated in Figs. 2 and 3, comprises a horizontal support 26 which in turn supports the shaft bearing 12.

Rigidly carried by the support 26 and frame portion F' in vertically disposed position is a cylinder 27 having a plunger rod 28 vertically movably disposed therein, and a coiled spring 29 is disposed within the cylinder 27 in surrounding relation to the plunger rod 28, the spring acting to normally urge the rod 28 downwardly as in Fig. 2.

A lever 30 is pivoted intermediate its ends to the upper end of the plunger rod, as at 31, and one end of the lever is pivotally connected at 32 to a bracket 33 secured to the frame portion F'.

The opposite end of the lever 30 is pivotally connected at 34 to one end of a link 35 whose opposite end is pivoted at 36 to one end of arms 37, whose opposite ends are secured to the shaft 10. The lever 30 is preferably longitudinally slotted at 31' for reception of pivot 31 whereby to provide for free swinging movement of lever 30 about the pivot 32.

The disposition of the parts 27 to 37 indicated in Fig. 2 is the relation when the latches are in latched position wherein arms 22 are substantially horizontally disposed and the rods 20 are moved laterally outward in urging the latches clockwise into latched position.

The springs 29 normally maintain the parts including the latches in the position of Fig. 2, suitable stop means being provided to limit downward movement of rods 28.

To release the latches by power, the plunger rod 28 at one or the other side of the car may be raised as by a hydraulic jack or by rigid cam means as disclosed in my co-pending application.

Upon raising the rod 28 the shaft 10 will be rotated counter-clockwise by the lever 30, link 35 and arms 37, as in Fig. 3, with a corresponding upward movement of arms 22 and the release of the latches by the rods 20.

Upon relieving the plunger rods 28 of upward pressure by means of the hydraulic jack or rigid cam, the compressed spring 29 will move the shaft 10 clockwise and thereby move the latches

to their latched position indicated in Fig. 2. The latches according to the present invention are capable of being retracted by manual means which, as indicated in Figs. 1, 4 and 5, comprises a bar 40 disposed at each side of the car or frame F and normally positioned parallel with the car side wall as indicated in Figs. 4 and 5. Each bar 40 is pivotally connected at 41 to a bracket 42, and the bar is formed at its free end in the form of a handle 43 for hand grasping by an operator.

Each bar 40 is maintained in normal inoperative vertical position by means of a link 44 supported by a stirrup 45 secured to the car side wall and the link by sliding engagement with the stirrup detachably engages the handle 43 as indicated in Fig. 4.

Each bar 40 is flexibly connected as by a chain 46 to one end of a rod 47 extending through a guide 48, and whose opposite end is pivotally connected at 49 to the outer ends of arms 50 which are rigidly connected to the shaft 10.

Thus it will be seen that the shafts 10 are capable of being rotated by the handle bar 40 as well as the power means 25, and that when the shafts are operated by the power means the chains 46 permit movement of rods 47 toward the handle bars 40 without affecting same.

It is, of course, to be understood that when the shafts 10 are rotated by manipulation of the handle bars 40 the plunger bars 28 are moved upwardly against the action of springs 29 which later move the latches to latched position.

The invention further includes novel means for locking the latch operating shafts 10 against rotation and such means comprises a vertically disposed horizontally elongated lock plate 52 rigidly attached to one end of a rod 53, whose opposite end is pivotally connected at 54 to the free end of an arm 55 which is rigidly connected to shaft 10.

A bracket 56 is rigidly supported by each car side wall, and the bracket includes a horizontal plate 57 provided with vertically disposed apertured flanges 58. A bolt 59 is slidably and rotatably disposed within the apertures of the flanges 58, and is provided with a manipulating handle 60.

The lock plate 52 is slidably disposed on the plate 57 and is provided with an aperture 61 for receiving the bolt 59 when aligned with the apertures in the flanges 58.

The right hand shaft 10 is locked against rotation in Fig. 4 wherein the bolt 59 is extended through the aperture 61 as is also indicated in Fig. 6. The plate 57 is provided with a notch 62 in its front edge which receives the bolt handle 60 when the bolt is in locking position. To release the safety lock, the handle 60 is grasped and rocked upwardly out of the notch 62 whereupon the bolt 59 is moved axially out of the aperture 61 as in Figs. 5, 7 and 8, thereby freeing shaft 10 for rotation either by the power operated means 25 or the manually operated bar 40.

It is to be particularly observed from Fig. 1 that the manual operating means and safety lock for either shaft 10 is disposed in adjacency at the side of the car adjacent the other shaft 10 which is provided with similar manual operating means and a safety lock at the other side of the car.

In operation, the car is positioned in a dumper. A hold-down device is then attached to the car at the side which is to be raised for dumping, and the thus held side is then raised by suitable hydraulic means for discharge of the load from the other, or lower side of the car.

The safety lock is then released by withdrawal of the bolt 59 after which the latches 14 at the low side of the car are released either by means 25 or upon pulling the handle bar 40.

From the above it will be apparent that there is provided a latch operating mechanism for railway dump cars well adapted to perform its intended functions, and while the invention has been described in detail, it will be apparent that numerous changes may be made in the specific construction disclosed, and it is contemplated to cover all such and to be limited in this respect only as may be necessary within the scope of the subjoined claims.

What I claim and desire to secure by U. S. Letters Patent is:

1. In a latch operating mechanism for a railway dump car having a door hinged at its upper end for outward swinging of its lower end, and a latch engageable with the lower end for normally retaining the door closed, a shaft extending lengthwise of the car and rotatably supported beneath the floor thereof, operative connections between the shaft and latch for closing the latch upon rotation of the shaft in one direction and releasing the latch upon rotation of the shaft in the opposite direction, yieldable means normally urging the shaft in said one direction, power operable means connected with the shaft for rotation thereof in said opposite direction against the action of said yieldable means; the improvement comprising a hand operable bar pivotally supported by a side of the car, and operable connections between the bar and said shaft for rotation thereof in said opposite direction for releasing the latch, said operable connections including a flexible member permitting rotation of the shaft by the power operable means in said opposite direction.

2. The structure according to claim 1 wherein said operable connections comprises a rod extending transversely of the car beneath the floor thereof, arms rigid with the shaft and projecting radially therefrom, one end of said rod being pivotally connected to said arms, and a chain providing said flexible member having one end thereof connected to the opposite end of said rod and the other end thereof connected to said bar.

3. Latch operating mechanism for a railway dump car having a door hinged at its upper end for outward lateral swinging of its lower end, and a latch engageable with the lower end for normally retaining the door closed, comprising a shaft extending lengthwise of the car and rotatably supported beneath the floor thereof, operative connections between the shaft and the latch for closing the latch upon rotation of the shaft in one direction and for releasing the latch upon rotation of the shaft in the opposite direction, yieldable means normally urging the

shaft in said one direction, and power operable means connected with the shaft for rotation thereof in said opposite direction against the action of said yieldable means, said power operable means comprising arms projecting radially from the shaft, a link having one end thereof pivotally connected to the arms, a lever having one end thereof pivotally connected to the other end of the link, the other end of the lever being pivotally connected to a rigid support, and a vertically disposed plunger having its upper end pivotally connected to said lever intermediate the opposite ends thereof.

4. The structure according to claim 3, together with a cylinder rigidly supported beneath the car floor and in which said plunger is reciprocally disposed and said yieldable means is disposed in said cylinder and bears on said plunger for normally urging same downward.

5. In a latch operating mechanism for railway dump cars including a shaft rotatably supported by the frame of the car beneath the floor thereof; the improvement comprising an elongated rod disposed beneath said floor, and an arm rigid with the shaft and projecting radially therefrom, a pivotal connection between one end of said rod and said arm, and a safety lock mechanism supported by a side wall of the car operatively associated with the opposite end of said rod for selectively permitting rotation of said shaft or locking same against rotation.

6. The structure according to claim 5, wherein in said safety lock mechanism comprises a vertically disposed and horizontally elongated apertured lock plate rigid with said opposite end of the rod, a pair of vertically disposed apertured flanges between which said plate is slidably disposed, and a manually operable bolt engageable in the apertures in said plate and said flanges for locking said rod against movement.

7. The structure according to claim 6, together with a third apertured vertical flange, said third flange and one of said pair of flanges providing support for the bolt when withdrawn from the aperture in said lock plate, and a horizontal plate at the bases of said flanges, a manipulating handle extending radially from said bolt, and a notch in said plate for receiving said handle when the bolt is in lock plate engaging position.

50
